UNITED STATES PATENT OFFICE.

GEORGE E. MARLATT, OF PASADENA, CALIFORNIA.

TYPOGRAPHICAL DISTRIBUTING MACHINE.

Application filed November 13, 1926. Serial No. 148,302.

My invention relates to typographical machines of the kind employing matrices which are released from a magazine in the assembling operation and restored to their individual channels in the magazine from which they were withdrawn following their use in a casting operation. My present improvements in such machines are directed to the font-distinguisher which is employed 5 to prevent matrices of one size or design from being distributed into a magazine intended for a different size or design.

In common practice there are six positions on the lower end of the matrices any one of 15 which may be occupied by the font notch. But there are twenty-one or more point-sizes of matrices and each size may be differentiated into several designs. Hence a single font-notch position has been made to 20 serve for several sizes of matrices and the several designs in each size, with the result that the font-distinguisher does not serve its purpose with regard to those fonts which have the distinguishing notch in the same 25 position. For example, 10-point, 13-point, 20-point, and 30-point matrices employ the same position for the font notch, and if each of these four sizes are made in three designs, then the single font-notch position must 30 serve for twelve fonts. Heretofore the six font-notch positions have been disposed at one side only of the longitudinal center of the matrices, the purpose being to have the font distinguisher element serve its purpose 35 in the event of a matrix being accidentally reversed in position about its longitudinal center.

My objective is to retain the usual font notches in their usual positions but to supplement them with a second notch or a second and third notch, and to provide a series 40 of font-distinguisher instead of the single adjustable distinguisher heretofore employed. And since matrices now in use 45 must frequently be employed in the same machine with the multiple-notch matrices now contemplated, I therefore provide that the new system does not interfere with the old. A further purpose is to provide means whereby a wrong-font matrix may be readily 50 removed from the distributor after having been stopped against the font distinguisher. I attain these objects by means of the devices illustrated in the accompanying 55 drawings, in which—

Fig. 1 is an elevation of the usual distrib-

utor box, showing its relation to the distributor bar and magazine entrance, with my invention applied; Fig. 2 is a perspective of the matrix-lift; Fig. 3 is a front elevation of the matrix-lift in position to lift a matrix having two font notches; Fig. 4 is an edge view of the matrix-lift in position to lift a matrix having special form of font notch; Fig. 5 is an edge view of the matrix lift as thrown out of lifting position by a reversed matrix having a special form of font notch; Fig. 6 is an edge view of the matrix-lift showing how it may be caused to lift a wrong-font matrix after having been 60 thrown out of lifting position thereby; Fig. 7 is a view taken on the line 7—7 of Fig. 1.

The matrices X are pressed by a pusher 1 against the vertical shoulders 2 on a pair of lower rails 3 and similar shoulders 4 on a pair of upper rails 5, the shoulders being engaged only by the ears of the matrices; when thus stopped the matrices are lifted one at a time to cause their ears to clear the shoulders 2 and enter the threads of the distributor screws 8, the reciprocations of the lifting element B being controlled by a cam 6 on the end of one of the distributor screws, all in the usual manner. Also in usual manner, the matrices rise on the inclined upper 75 edges of the rails 5 until their distributing teeth engage the longitudinal ribs on the distributor bar 7, remaining under control of the distributor screws 8 until they are released into individual channels in the 80 magazine entrance 9. In the absence of the special provision to be described, when a wrong-font matrix has been lifted into engagement with the distributor screws it cannot be readily removed until it arrives at a 85 point above its individual channel or enters therein; also, if stopped against the usual 90 distinguisher point or blade the whole line of matrices must be backed out of the distributor box 10 in order to remove the 95 wrong-font matrix. As hereinafter explained, according to the provisions of my 100 present improvements the wrong-font matrix will be the foremost matrix in the distributor box and under manual control may be caused to be lifted into engagement with the distributor screws. In order that it may be then removed I provide in the distributor bar 7 a vertically movable section A. The ribs A¹ on this movable section are normally 105 in alignment with those on the main portion of the bar 7; but since the ribbed edge of

the bar is of V-shape in cross section a slight upward displacement of the section A will place it above engaging relation with the teeth X² in the V-notch of the matrices and 5 the matrices so freed from engagement will drop from the end of the pair of rails 5 into the hand of an operator or into a suitable receptacle. The section A is pivoted to the horizontal arm of an angular lever A² and 10 is normally held in and returned to its down position by means of a spring A³, but when the lever is rocked about its pivot A⁴ against the tension of the spring the section A will be raised to the position shown in 15 the drawing. Its downward movement is limited by contact of the lever A² with a stud A⁵.

In lieu of the usual single font-distinguisher point mounted between the rails 3 20 in advance of the shoulders 2, I provide two different series of six distinguishers each, but the numbers given may be varied to meet varying requirements; also, both series 25 may be alike, or there may be a single series of one form, according to requirements.

The distinguishers C of one series are mounted on the lift B and reciprocate therewith each time a matrix is lifted. As illustrated in Fig. 3 their positions individually 30 correspond to the usual six positions occupied by the usual font-notch X¹ on the matrices. Near their lower end each distinguisher is provided with a tooth C¹ and when this tooth is engaged with an upper 35 groove B¹ in the lift the distinguisher thus raised becomes operative by reason of the fact that its distinguisher point C² is above the lifting shoulder B³ on the lift. When thus operative, only those matrices having 40 a font notch corresponding in position with the operative distinguisher point will permit the shoulder B³ on the lift to enter beneath the foremost matrix when stopped against the shoulders 2 of the rails. When 45 in its down position the lift is pressed by a spring 11 against a stop 12 with its lifting shoulder entered just beneath the forward edge of the foremost matrix: hence a wrong-font matrix will not permit the lift to thus 50 enter beneath the matrix but will keep the lift deflected as shown in Fig. 5. If, however, it is desired to lift a wrong font or 55 reversed matrix, the lift may be pressed beneath the matrix as shown in Fig. 6, and the matrix will then be lifted and may be removed from the distributor bar as hereinbefore explained. Another method of lifting a wrong font matrix is illustrated in Fig. 1 which shows a matrix being lifted 60 on and by the distinguisher point, the distinguisher point having been caused to enter beneath the matrix by pressing down on the lift lever 13 against the resistance of a spring 14. It will be understood that 65 any one or more of the ditsingishers C may

be lifted from the lower notch B² to the upper notch B¹ and rendered operative in connection with matrices having font notches in corresponding number and positions. The distinguishers are packed in a keeper D which spans the lift B and is held in proper position thereon by reason of its engagement with grooves B⁴ in opposite edges of the lift. The spring 11 serves to 70 press the distinguishers against the back of the lift and they are moved from one to another position in the notches B¹, B², against the resistance of this spring. Their lower ends are made angular in alternating directions for convenience in handling 75 them.

Unlike the series C, the second series E of distinguishers do not move with the lift B but remain stationary except when swung to or from operative position. To accommodate them the lift B is provided with a clearance notch B⁵. They are pivoted on a rod E¹ and stopped against a rod E² whether in operative or inoperative position. In order that they may not become displaced laterally they are packed between one of the rails 3 and a sleeve E³ on their pivot rod. Unlike the movable distinguishers C the stationary ones E hold a wrong-font matrix away from the rail shoulders 2, but the wrong-font will be the foremost matrix in a line and it can therefore be freed for lifting by merely swinging the distinguisher to inoperative position; or, the matrix may be raised manually to clear the distinguisher. 100

In connection with the usual form of matrix font notch, the chief advantage in providing the series of stationary distinguishers mounted back of the lift instead of the single adjustable distinguisher point usually provided in front of the lift, resides in the fact that a wrong-font matrix is stopped in the first position adjacent the shoulders 2, whereas by the old method the wrong-font would be the second or third matrix 105 from the shoulders according to thickness, and could not be removed except by backing the line from the box 10; also, the single distinguisher point is easily broken and subject to accidental displacement or mis-adjustment. But the present invention contemplates a new form of matrix font-notch, and the new forms of distinguishers, C and E, have a distinct use in connection therewith. 110

Unlike the usual front notch, my new form of matrix font-notch F is cut only part way through the matrix. A matrix having two such notches each placed an equal distance from the longitudinal center of the matrix for co-operation with two distinguishers in similar position would be properly stopped if presented in reversed position as in Fig. 5, and in this respect this form F is an improvement over the usual 125 130

form X^4 of notch. Further, if the usual form X^1 be employed in connection with the usual form of distinguisher (not shown) for the purpose of distinguishing point sizes, then the new form F may be employed in connection therewith for distinguishing between different styles of a single point size. For example, three fonts of 10-point, as 10-pt., No. 1, 10-pt., No. 2, 10-pt., No. 3, would all have the usual font notch X^4 in the same position, and in addition the new form F in a different position for each kind of 10-pt.; hence the new form of distinguisher, C or E, in connection with the new form of notch F would prevent one kind of 10-pt., from being inadvertently mixed with another kind of 10-pt. Further, if the old form of notch were reserved for use alone in connection with a single size of matrices, then the new form of notch could be employed in connection with the other sizes which have heretofore had the font notch in the same position. For example, 6-pt., 12-pt., and 24-pt., could, as heretofore, employ the same font-notch position, and in order to prevent these three sizes from becoming mixed the 12-pt. could have the new form of notch F in a position to cooperate with one of the distinguishers E, and the 24-pt., could have a notch F in position to co-operate with one of the distinguishers C. A further advantage in the new form of notch is the fact that it may be placed in the exact center of a matrix and still serve its purpose in the event of the matrix becoming reversed. Another advantage is that both the old and new form of distinguishers may be employed, one style or size of matrix having the old form of notch and another style having the new form in the same position, in which case the old form of distinguisher would stop a wrong-font having the new form of notch, and the new form of distinguisher could be thick enough to stop a wrong-font having the old form of notch. Or, the stationary new form E of distinguishers could be in the plane occupied by the old form of notches and made long enough (as at E⁴) to hold a matrix away from the shoulders even though it carried the new form F of notch in alignment with the new form E of distinguisher. This latter arrangement could be employed to keep matrices of a certain kind out of a certain machine according to the position of the two forms, C or E, of distinguishers relative to opposite sides of the center of the lift B. In this connection it may be noted that a single distinguisher of the new form E may be mounted on a longitudinally movable shaft and rendered automatically adjustable in the manner disclosed in Patent No. 1,126,543 and similar disclosures, and the other form C could be employed to co-operate and would not interfere with the automatic feature. Also, in my application

resulting in Patent No. 1,266,970, means are shown for rendering a single distinguisher adjustable on the lift B.

Having thus described my invention, and its advantages, what I claim as new and desire to secure by Letters Patent, is: In a typographical distributing machine

1. A distributor bar having an intermediate section thereof movable to predetermine the engagement or nonengagement of matrices relative to said distributor bar beyond said movable section thereof.

2. In combination with a distributor bar and matrices capable of engaging said bar for suspension therefrom, means for preventing said matrices from engaging said bar, said means consisting in rendering a portion of said bar movable out of engaging position relative to said matrices.

3. In combination with matrices having font notches in varying positions and a lift for raising said matrices into engagement with distributing means, a font distinguisher carried by said lift for permitting or preventing the lift of said matrices according to the position of the font notches thereon.

4. In combination, matrices having font-distinguishing notches in varying positions and numbers thereon according to font, a lift for raising said matrices to distributing level, a series of font distinguishers on said lift, and means for rendering certain of said distinguishers operative and others thereof inoperative according to the number and position of the font notches on an active font of said matrices.

5. In combination, matrices having font-distinguishing notches thereon, a matrix lift having a front distinguisher thereon and capable of causing said lift and said distinguisher to be deflected and thus prevent the lifting of a matrix of wrong font as determined by the position of its font notch, and means whereby said distinguisher may remain deflected while said lift is manually moved and caused to lift a wrong-font matrix without disturbing the adjustment of said font distinguisher.

6. In combination, a reciprocating matrix-lift B, having a lifting shoulder B², a font-distinguisher mounted on said lift for reciprocating movement therewith and having its font-distinguishing point C² above said lifting shoulder.

7. In combination, matrices having font-distinguishing notches thereon in various positions according to font, shoulders against which said matrices are stopped preliminary to their disengagement therefrom, a lift for disengaging said matrices from said shoulders, and a font-distinguisher mounted beyond said shoulders and said lift and terminating in advance of said shoulders for the purpose of preventing said matrices from

engaging said shoulders and being lifted by said lift in the event that their font-distinguishing notch does not correspond in position with said font distinguisher.

5. 8. A combination as specified in claim 7 characterized by the fact that the font-distinguishing notch on the matrices therein recited may be of either one of two forms, one form F thereof extending partly 10 through said matrices and the other form X¹ thereof extending through said matrices, that said two forms of notch may occupy the same position on two fonts of matrices, and including a font-distinguisher of the 15 kind specified but extending beyond said shoulders a sufficient distance to obstruct matrices having the first mentioned form F of notch while permitting those having the other form to engage said shoulders and to 20 be engaged by said lift.

9. In combination, matrices having font notches thereon in varying positions according to font, shoulders against which said matrices are stopped, a lift for disengaging said matrices from said shoulders, and a series of font distinguishers pivotally mounted beyond said lift and capable of being swung selectively to or from a position in advance of said shoulders according to the position of the font notch on an active 25 font of matrices.

10. A combination as specified in claim 9 characterized by the fact that the font distinguishers in the series thereof therein recited may vary in length or thickness according to the form of font notch with which they are intended to co-operate. 30

Signed at Pasadena, Los Angeles County, California, this 19th day of October, 1926.

GEORGE E. MARLATT.
